US00D999758S

(12) **United States Design Patent** (10) **Patent No.:** **US D999,758 S**
(45) **Date of Patent:** **** Sep. 26, 2023**

(54) **VIDEO CONTROLLER**

(71) Applicant: **Shenzhen Lingan Wireless Technology Co., Ltd**, Shenzhen (CN)

(72) Inventor: **Jianbing Su**, Shenzhen (CN)

(73) Assignee: **Shenzhen Lingan Wireless Technology Co., Ltd**, Shenzhen (CN)

(**) Term: **15 Years**

(21) Appl. No.: **29/849,888**

(22) Filed: **Aug. 15, 2022**

(51) LOC (14) Cl. **14-03**

(52) U.S. Cl.

USPC **D14/218**

(58) **Field of Classification Search**

USPC D14/218, 203.3, 400, 496, 125; D13/168

CPC G06F 3/014; G06F 3/0202; A63F 13/24

(57) **CLAIM**

The ornamental design for a video controller, as shown and described.

DESCRIPTION

FIG. 1 is a perspective view of a video controller, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the video controller that form no part of the claimed design.

1 Claim, 8 Drawing Sheets
